188,999

PORTABLE ELECTRIC CORE DRILL.

Edward W. Ristow, Wauwatosa, and Hans J. Fick, Milwaukee, Wis., assignors to Milwaukee Electric Tool Corporation, a corporation of Wisconsin

Filed June 1, 1959, Ser. No. 56,173

Term of patent 14 years

(Cl. D54—14)

Fig. 1 is a front and side perspective view of a portable electric core drill embodying our new design; and

Fig. 2 is a rear and side perspective view of the same portable electric core drill.

The side not shown is substantially a mirror image of the side shown in Fig. 2 except for the actuating handle; and the dominant features of our design reside in the portions shown in full lines.

We claim:

The ornamental design for a portable electric core drill, substantially as shown and described.
